MERCURY POOL DAMPING MEANS

Ernest G. Bangratz, Churchill Borough, Pa., assignor to Westinghouse Electric & Manufacturing Company, East Pittsburgh, Pa., a corporation of Pennsylvania

Application January 21, 1937, Serial No. 121,590

3 Claims. (Cl. 250—27.5)

My invention relates to arc discharge devices, and especially such devices utilizing a mercury pool as a cathode.

An object of my invention is to prevent waves in a freely exposed mercury surface especially where an auxiliary starting electrode is immersed in the mercury pool.

Other objects and advantages of the invention will be apparent from the following description and drawing, in which:

Figure 1 is a view principally in cross section illustrating the difficulties with prior art construction;

Fig. 2 is a view of the apparatus of Fig. 1 modified in accordance with my invention; and

Fig. 3 is another view of the apparatus of Fig. 1 with a still further modification of my invention.

Difficulties have arisen due to the creation of waves and oscillations in the mercury pool type of arc discharge device, in which a starting electrode immersed in the mercury pool is utilized. This trouble is especially prevalent where such tubes are used for welding purposes due to the peculiarity of the load.

This trouble concerns both the sealed off type glass tubes and the large continuously pumped metal tanks. The welding load requires, in general, the periodically repeated group of conducting half cycles for each tube or there may be an irregular intermittent group of conducting half cycles in the bigger metal tanks. The number of conducting half cycles per group depends upon the type of work to be done, namely, the materials that are to be welded and their thickness.

The number of groups depends upon how fast it is desired to perform the work, in other words, how many welds may be made per minute.

In Fig. 1 is illustrated a type of arc discharge device which has been found especially suitable for the control of welding apparatus. The container 10 is illustrated in this case as of glass and containing the anode 11 with its lead-in 12 and a mercury pool 13 with its cathode lead-in 14.

It will be understood that mercury is used since it is the common material of this type of device and that amalgams and other liquid metals are considered the full patent equivalent thereof. A make alive starter assembly 15 is disclosed with the tip 16 of high resistance material, such as 50 carborundum or boron carbide normally immersed in the surface of the mercury.

The cathode spot which always starts at the junction of the mercury 13 and the starter electrode 16 during the conductive half cycles in a single weld sets up waves in the mercury. The

height of these waves at the location of the starter depends upon the intensity of the current during each conductive half cycle in the weld or "shot", the number of half cycles per shot and the dimensions of the pool. Also these waves are further complicated by the continued existence for each entire half cycle of the erratically wandering cathode spot which acts as the continuous source of waves whose positional origin is varying from instant to instant. A wave, such as that disclosed in Fig. 1, may occur in which the mercury is not in contact with the starting electrode 16. If at this moment, it is desired to fire the tube, the tube would not function. It is also possible that if the tip of high resistance material 16 were very short that a big wave would occur that would strike the other portions of the starting electrode assembly 15 and the starter 16 will be shorted. To further complicate matters, the repeated group shots may and do set the whole mass of the mercury pool into oscillation upon which is superimposed the higher frequency waves previously described. The resultant wave will expose the tip of the starting electrode 16. The tube will be inoperative if it is desired to start the tube at this particular moment. The mass motion of the pool as a whole is much dependent upon the intensity of the shots and their frequency per minute. If the starter is put in an off center position, it will be apt to aid and enhance the mass oscillation of the mercury pool.

It is an object of my invention to eliminate improper operation due to pool agitation by providing proper damping means of the pool. One such means is illustrated in Fig. 2, which has the anode 11, mercury pool 13 and starter electrode 16 similar to Fig. 1. It will be noted that in Fig. 1, the main reservoir 17 for the mercury pool is rather large and also the mercury pool has a fair depth around the sides 18 about this central reservoir. In Fig. 2, however, while I utilize the same large central reservoir 17 for the mercury yet I utilize an amount of mercury that will make the depth at the sides 18' very shallow. Furthermore, I make the juncture between the large shallow part 18' and the reservoir 17 very sharp at 19. The result will be that a wave will be damped by the shallow portions 18' and by the sharp edge 19. The shallow part at 18' should be as wide as practical and flat and the depth should be as small as practical which is probably of $\frac{1}{4}$ " in magnitude. Cooling means applied to the bottom of the tube would be very effective on the shallow part 18'.

I prefer, however, to also utilize actual dampers. These dampers may take various forms and location but in Fig. 3, I have illustrated a preferred embodiment. This preferred embodiment is a ring 20 of apertured material either of perforated solid material or mesh. I prefer mesh screen of about 30 mesh located just below the mercury surface. This ring of mesh permits the mercury to pass therethrough but damps any rapid passage. The ring is held in position by supports 21 which may be strips of nickel spot welded to the ring and to the top of the lead-in 22. The lead-ins in the larger tubes are $\frac{3}{8}$ " molybdenum rods to which has been welded a nickel disk 23, preferably 1" in diameter, which helps collect the current from the mercury. The damping grid should extend from the pool edge radially inward a distance which may be but a fraction of the pool diameter. The damping grid need not have a hole in the middle of the diameter thereof but, if this hole is omitted, the damping grid should then be of molybdenum or tungsten and the starter electrode should not touch it. Otherwise the grid material may be of nickel, iron, etc. While in accordance with the patent statutes, I have described preferred embodiments of my invention, yet it is apparent that many changes may be made in the form and arrangement of elements without departing from the spirit of my invention. Accordingly, I desire only such limita-

tions to be imposed on the following claims as are necessitated by the prior art.

I claim as my invention:

1. An arc discharge device comprising a casing having an anode and a mercury pool as cathode 5 therein, an auxiliary starting device immersed in mercury pool during the normal operation of said device, said mercury pool having a surface freely exposed to the arc from the anode, and damping means for waves on said freely exposed 10 mercury surface located entirely below the surface thereof.

2. An arc discharge device comprising a casing having an anode and a mercury pool as cathode 15 therein, an auxiliary starting device immersed in said mercury pool during the normal operation of said device, said mercury pool having a surface freely exposed to the arc from the anode, and apertured damping means for waves on said freely 20 exposed mercury surface located entirely below the surface thereof.

3. An arc discharge device comprising a casing having an anode and a mercury pool therein, a lead-in immersed in said pool during the normal 25 operation of said device and annular damping means secured to said lead-in and an auxiliary starting electrode immersed in said pool in the central opening of said annular damping means.
